UNITED STATES PATENT OFFICE.

GEORGE E. RIDDLE AND WILLIAM QUEIROLO, OF SAN FRANCISCO, CALIFORNIA.

MOTION-PICTURE-FILM CONTAINER.

1,295,372.

Specification of Letters Patent. Patented Feb. 25, 1919.

Application filed March 11, 1918. Serial No. 223,236.

To all whom it may concern:

Be it known that we, GEORGE E. RIDDLE, and WILLIAM QUEIROLO, citizens of the United States, residing in the city and county of San Francisco and State of California, have jointly invented a new and useful Improvement in Motion-Picture-Film Containers, of which the following is a specification.

10 Our invention relates to containers for motion picture films and the like wherein pivoted containers operate to facilitate the safe handling of motion picture films during transportation.

15 One of the objects of our invention is to safeguard highly inflammable and combustible motion picture films both during transportation and also while in the operating room.

20 Another object of the present invention is to provide a shipping and dispensing container that is simple, cheap and fireproof and one that will facilitate the discharge and retention of films. Also to provide a

25 container that will be automatically closed and locked by introducing a film thereby preventing the exposure of said film to destruction by fire, accumulation of dust or other debris.

30 It is a further object of our invention to provide a dispensing container that will automatically remain in an open or discharging position while empty.

Another object is to provide such containers in the form of unit construction wherein the respective units will be assembled in convenient form for transportation, and, when a cover is removed will be readily accessible for selective use.

40 A further object is to provide a device of the character described wherein the individual containers will be pivotally mounted in eccentric relation to the axis of the roll of films to be stored in order to utilize the 45 weight and gravitation of said film to open and close said device; and also

To provide, in a film container, a humidor adapted to prevent the films from becoming too dry and cracking.

50 We accomplish these several features by means of the device disclosed in the drawings forming a part of the present specification wherein like characters of reference are used to designate similar parts through-

out the said specification and drawings, 55 and in which—

Figure 1 is a broken perspective view of our improved device disclosing one container in a discharging and another locked in a retaining position. 60

Fig. 2 is an enlarged transverse sectional view of the container disclosing one of the units in a locked retaining position;

Fig. 3 is a similar view disclosing the unit in a discharging position; 65

Figs. 4 and 5 are a front and side elevation respectively modified of a form of the invention;

Fig. 6 is a bottom plan view of one of the covers disclosing the moisture retaining 70 means;

Fig. 7 is a side elevation of Fig. 6;

Fig. 8 is an enlarged sectional view taken on line 8—8 of Fig. 6; and

Fig. 9 is an enlarged sectional view in 75 detail of a portion of one of the containers disclosing the method of fireproof construction.

Referring to the drawings the numeral 1 is used to designate a suitable rectangular 80 frame surrounded with a housing 2. The frame 1 is provided with a plurality of forwardly and downwardly inclined braces 3 reaching from the upper back portion to the lower front portion of the frame 1 and provided at their approximate central portions with bearings or journals 4.

Between each pair of adjacent journals 4 are pivotally mounted motion picture film containers designated in general by the numeral 6.

In order to provide adequate protection against fire to the films contained within the containers 6, and for other purposes hereinafter set forth, said containers are 95 formed preferably of two side pieces 7, which are rectangular with semicircular ends, and a strip 8 which forms a semicircular bottom and end pieces between the sides 7, said strip 8 being secured to the 100 pieces 7 by means of double lapped joints 9 as disclosed in Fig. 9 of the drawings.

By means of this arrangement there are no soldered seams to be melted in case of fire or heat from a fire so that the contents 105 of the containers 6 will therefore be protected as the double lapped joints or seams 9 will hold the containers together.

Each container 6 is pivotally mounted between adjacent bearings or journals 4 by means of trunnions 11 which are situated below and diagonally from the center of gravity of each container 6 whereby said container will be automatically retained by means of the attraction of gravity, either in a vertical retaining or in a substantially horizontal discharging position as disclosed in Figs. 2 and 3 respectively, and limited to either position by the frame 1.

Each container 6 is open at the top thereof said top being provided in the preferred form of the invention with a top or cover 12 hingedly mounted at the back portion of the container 6 so that said cover will automatically swing open when said container 6 is in a discharging position and swing shut when in a retaining position.

Each cover 12 is provided with a spring latch 14 having a recess 16 arranged to engage the upper front portion of the frame 1 and thereby automatically lock the cover 12 and the container 6 in a retaining or shipping position. Each latch 14 is provided with a ring 17 by means of which said latch may be disengaged from the frame 1. By referring to Fig. 2 of the drawings it will be observed that by pulling downward on the ring 17 the recess 16 of the latch 14 will be disengaged from the front of the frame 1 and the container 6 will be moved upon its trunnions 11 to the discharging position disclosed in Fig. 3 of the drawings.

In order to keep the films moist during transportation or storage we have provided the cover 12 with a humidor attachment 18 containing a suitable absorbent material for the retention of moisture. The attachment 18 is perforated as at 19 to permit the permeation of the interior of the container 6 with fumes or vapor from the said humidor 18.

This feature is provided as it has been found in practice that motion picture films tend to become dry and crack easily during long periods of transportation or storage. By supplying a humidor to impart a proper degree of humidity to the interior of the container 6 the films are prevented from becoming dry and from cracking.

A suitable door 21 is hingedly mounted to the front lower portion of the frame 1 and the bottom of the housing 2 therefor by means of which the entire frame may be inclosed for transportation or storage purposes.

The frame 1 is also provided with folding legs 22 pivotally mounted upon each corner of the frame 1. The legs are retained in a supporting position, while the container is in an operating room, by means of suitable braces 23 hingedly connected to one set of legs and having a slot 24 in the opposite ends thereof to engage lugs 26 in the adja-

cent legs as disclosed in Fig. 1 of the drawings. During transportation these legs 22 may be folded to facilitate handling of the frame 1.

It is obvious that as the containers 6 are pivotally mounted below and diagonally from their centers of gravity that the force of gravity will tend to automatically retain said containers in either an upright retaining or a substantially horizontal discharging position as disclosed in Figs. 2 and 3 of the drawings.

Therefore, when a film roll has been removed from a container, when in a discharging position, said container will be automatically retained in that position thus indicating to the operator the container within which the reel, to be returned belongs.

The containers 6 are so mounted within the frame 1 that when in a discharging position the lower portion or floor of the interior of that container will be slightly inclined to facilitate removal of the reel of film from within.

Therefore, the door or cover 12 of a container 6 in discharging position will tend to swing open thus rendering that container conspicuous as may be observed by referring to Fig. 1 of the drawings.

When a reel of film, indicated in dotted lines in Fig. 2 of the drawings, is returned to a container the center of gravity of the combined reel, film and container is automatically placed back of the trunnions 11 and therefore the container is automatically returned to a vertical retaining position and automatically locked in that position by the engagement of the recess 16 of the latch 14 with the front upper portion of the frame 1.

In Figs. 4 and 5 we have illustrated a modified form of the invention wherein the doors 12 are hingedly mounted at one side thereof instead of at the end as disclosed in the preferred form of the invention.

It is obvious from the foregoing that we have provided an improved motion picture film containing and dispensing device having improved means for automatically locking the containers in a closed and retaining position as well as improved means for automatically retaining said containers in a discharging position to indicate the container to which a removal reel of film is to be returned.

Having thus described our invention what we claim as new and desire to secure by Letters Patent is—

1. A motion picture film container open at the top thereof and pivotally mounted at a point situated below and diagonally from the center of gravity of said container whereby said container may be automatically retained in a vertical retaining position or a substantially horizontal discharg-

ing position; and means for limiting the movement of the container about its pivotal point; and a cover hingedly mounted upon the container and arranged to swing open when said container is in a discharging position and to close when said container is returned to a retaining position; and means secured to the cover to lock the container in a retaining position.

2. The combination with a suitable frame of a plurality of containers each having an open top and pivotally mounted within the frame at a point situated below and diagonally from its center of gravity whereby said container may be automatically retained in a vertical retaining or a substantially horizontal discharging position, said frame being arranged to limit the movement of said containers to either position; a cover hingedly mounted upon the top of each container and arranged to swing open when said container is in a discharging position and to swing shut when said container is moved to a retaining position; and means mounted upon each cover to automatically lock said cover shut and to retain the container in a retaining position when said container is swung to said retaining position.

3. The combination with a suitable frame of a plurality of motion picture film containers each having an open top and pivotally mounted within the frame at a point situated on each container below and diagonally from its center of gravity whereby said container may be automatically retained in a vertical retaining or a substantially horizontal discharging position, the

frame being arranged to limit the movement of said containers to either position; a cover hingedly mounted upon each container and arranged to swing open when said container is in a discharging position and to swing shut when said container is in a vertical or retaining position; and a spring latch mounted upon each cover to automatically engage a portion of the frame to lock the cover and container in a retaining position.

4. The combination with a suitable frame of a plurality of motion picture film containers each having an open top and pivotally mounted within the frame at a point situated on each container below and diagonally from its center of gravity whereby said container may be automatically retained in a vertical retaining or a substantially horizontal discharging position, the frame being arranged to limit the movement of said containers to either position; a cover hingedly mounted upon each container and arranged to swing open when said container is in a discharging position and to swing shut when said container is in a vertical or retaining position; and a spring latch mounted upon each cover to automatically engage a portion of the frame to lock the cover and container in a retaining position; a suitable housing around the frame; a door hingedly mounted to the lower front portion of the housing and frame; and suitable folding legs to support the frame and housing.

In witness whereof we hereunto set our signatures.

GEORGE E. RIDDLE.
WILLIAM QUEIROLO.
